WIDE BAND AMPLIFIER

George C. Sziklai, Princeton, N. J., assignor to
Radio Corporation of America, a corporation
of Delaware

Application December 29, 1944, Serial No. 570,295

3 Claims. (Cl. 179—171)

1

The present invention relates to amplifying systems, and more particularly to an improved wide band amplifier coupling network suitable for use as a video amplifier in television systems and circuits.

In television systems and circuits it is necessary to amplify signal frequencies occupying a wide range of the frequency spectrum from the very low frequencies up to frequencies of three or four megacycles. It is by now well known that the gain of an amplifier stage may be made more uniform over a given frequency range by employing filter circuits as an inter-stage coupling means. It is also well known that the product of the band width and the amplification ratio is dependent primarily on the transductance of the amplifier tube and of the capacities to ground. The product of the band width and the amplification ratio is limited by the ratio of the transductance G_m/c , in which c is the shunt capacitance. The effect of the shunt capacitance decreases as the frequency increases. For example, the reactance of the shunt capacitance, whether it is the inherent capacitance of the tube or a separate physical condenser, decreases at a fairly uniform rate as the frequency is increased. By using filter circuits, one may provide a more nearly constant gain over the pass band of the filter, the problem then being to increase the width of this pass band without undue sacrifice in other directions. A solution offered by the present invention is to increase the gain by effectively employing gain-band width area in a novel manner to be explained.

Accordingly, the major object of the present invention is to provide a simple and economical circuit means for efficient high frequency filter compensation.

Another and related object of the invention is to provide novel circuit means and to render the alignment of these circuit means easy of accomplishment.

A further object is to provide a filter circuit having a constant gain over the pass band, the gain being increased by adding the gain-band width area removed above the cut-off frequency to the area in the pass band.

Other objects and advantages of the invention will, of course, become apparent and immediately suggest themselves to those skilled in the art to which the invention is directed from a reading of the following specification in connection with the accompanying drawings in which:

Fig. 1 shows schematically a coupling circuit in accordance with the invention; and

2

Fig. 2 shows curves serving to illustrate the advantageous features of the circuits of Fig. 1.

Referring for the present to Fig. 1 of the drawings, 10 indicates a signal source, such as a vacuum tube amplifier, repeater or the like, the output of which is to be coupled to a succeeding stage or translating device (not shown) which may be connected to an output terminal 11. The grid 12 of the tube 10 is supplied with signals from a terminal 14 which may be connected to the output terminal of a preceding stage of amplification or to a source of image signals, such as a camera tube or the like. In the event that the grid 12 is connected to a preceding stage of amplification, it will be understood that a filter coupling arrangement, such as the filter 21, constituting the invention and to be described hereinafter, will be substituted for the simple arrangement shown which comprises a coupling condenser 16 and a grid resistor 18. Coupling between the output of the signal source 10, which, in the illustrative embodiment, is the plate circuit 19 of the vacuum tube 10, is effected by a circuit organization comprising the previously mentioned band pass filter 21. The filter is made up of series inductances 24 and 26 and parallel capacitances 27, 28, and 31. The capacitances 27 and 28 are shown by dotted lines and represent the inherent input and output capacitances of the stages to be coupled. In the present instance, the capacitance 27 is the anode-to-cathode capacitance of the tube 10, and capacitance 28 is the input capacitance of the translating device or succeeding stage which is in communication with the terminal 11. The filter 21 is terminated by a resistor 33.

The condenser 31 is a balancing capacitance having a value approximately equal to that of 27. An adjustable condenser 34 serves as a bridging capacitor for the filter and has a value of approximately

$$C_{34} = \frac{C_{28} - 2C_{27}}{4}$$

The output connection 11 is taken across the mid-shunt arm which comprises the condenser 28.

The filter 21 is formed from a constant-K type ladder filter with the aid of a bridging capacitor, and thus possesses a distinct advantage over the m -derived ladder filter which requires at least one additional inductor and is more difficult to adjust. Since filters of the constant K type have not provided sufficient gain over a sufficiently large portion of the frequency spectrum to permit their most efficient use, the relatively more

expensive m -derived ladder filter with the disadvantage noted has been employed.

By referring to the curves of Fig. 2, it will be shown that the bridged-T filter with the proposed terminal connections serves as well as a ladder type m -derived filter without attendant disadvantages. The curves of Fig. 2 are obtained by plotting frequency f against gain indicated as G on the ordinate scale. Curve 34 shows the gain obtained when a simple RC circuit is employed for coupling. An example of such a circuit would be the plate load resistor shunted by the cathode-to-plate capacitance of a vacuum tube. It will be noted that a very small part of the frequency range is useful since the gain falls off rapidly. Also, there is no well defined cut off region, and therefore, the area under the curve 23, while it is large, does not represent a useful gain-band width area.

An ideal response which may not be attained in practice is indicated by the rectangle 36. Here, the cut off point is abrupt and all of the gain-band width area is available. The area under the curve 34 is approximately equal to the area under the curve 36, it being remembered that curve 34 still lies above the zero axis at a remote point, theoretically, at infinite frequency. From these considerations it appears that to solve the problem of increasing the available gain-band width area, it is desirable to increase the gain obtained when a filter is employed by adding the gain-band width area removed above the cut off frequency to the area in the pass band.

Curve 38 is the curve which would be obtained by employing a two-section constant K filter, for example. This may be of the type employing a resistor and a peaking coil and capacitances, such as the inherent input and output capacitances of the input and output circuits and/or the inherent capacities of the inductive and resistive elements themselves. Very considerable improvement in gain at the higher frequencies is to be observed. However, this curve represents, but to a lesser degree, a non-usable portion of the curve in a region where attenuation is high at higher frequencies. Considering Fig. 1 of the drawings, a filter constituting only the elements 24, 26, 27, 28, and 31 with the output taken across the terminating resistor 33, would give a characteristic somewhat as shown by the curve 38. Some improvement would be obtained by connecting the output connection across the mid-shunt arm as shown.

In accordance with the invention, the capacitor 34, the value of which with respect to other circuit elements is discussed above, is bridged across the inductances 24 and 26, the result being a characteristic indicated by reference character 39. By adding this capacitor it will be observed that a considerable portion of the gain-band width area is removed above the cut off frequency and is made available in the pass band. Moreover, the curve 39 more nearly approaches the ideal curve 36.

The circuit just described is particularly useful when the capacitance 28 is greater than twice the capacitance 27, without the addition of capacitors, which is a common case.

While the bridged T network is known to be an economical filter, simpler in its adjustment than the comparable m -derived ladder type section, it has heretofore been used only with the output taken at its far end, that is to say, across resistor 33 which provides a high attenuation for a frequency outside the pass band. By taking the output across the mid-shunt arm in accordance with the present invention, a more efficient capacity distribution is obtained and the sharp cut off effect not only is retained but takes a more desirable form for video amplifier characteristics.

Various modifications of the invention shown and described herein by way of example are possible without departing from the spirit and scope of the described invention, and it is desired that any and all such modifications be considered within the purview of the present invention defined by the hereinafter appended claims.

Having now described the invention, what is claimed and desired to be secured by Letters Patent is the following:

1. A video amplifier employing a bridged-T network for high frequency correction comprising a signal source serving as an input for said network, said network being of the low pass type composed of inductors in series bridged by capacitors, a terminal resistor for said network, an output connection to said network at the location of an intermediate shunt arm, and an adjustable balancing capacitance bridged across said inductances in series whereby to cause the cut off of said network to be more abrupt so that a greater portion of the gain-band width area of the response curve of said network is available for signal transfer.

2. A video amplifier employing a bridged-T network for high frequency correction, the network comprising a pair of series inductances, shunt capacitances in said network effectively at the input and output ends of said inductances and at their mid-connection, an output connection provided across the capacitance at the mid-connection, and a capacitance bridging said inductances.

3. A video amplifier employing a bridged-T network as set forth in claim 2 in which the bridging capacitance is so proportioned with respect to the input and mid-shunt capacitances that

$$C_2 = \frac{C_0 - 2C_1}{4}$$

where C_2 is the bridging capacitance, C_0 is the mid-shunt capacitance, and C_1 is the input capacitance.
